DESIGN FOR A DRESS

William S. Wolfe, New York, N. Y., assignor to Franklin Simon & Co. Inc., New York, N. Y.

Application August 21, 1934, Serial No. 53,001

Term of patent 3½ years

To all whom it may concern:

Be it known that I, WILLIAM S. WOOLFE, a citizen of Great Britain, residing in the city of New York, county of New York, and State of New York, have invented the new, original, and ornamental Design for a Dress, of which the following is a specification, reference being had to the accompanying drawing, forming part thereof, wherein,

I claim:

The ornamental design for a dress, substantially as shown.

WILLIAM S. WOOLFE.
